UNITED STATES PATENT OFFICE.

ORRIN M. WHITMAN, OF BOSTON, MASSACHUSETTS.

REFRIGERATOR OR BUTTER-COOLER.

SPECIFICATION forming part of Letters Patent No. 279,296, dated June 12, 1883.

Application filed February 26, 1883. (No model.)

To all whom it may concern:

Be it known that I, ORRIN MILO WHITMAN, of Boston, in the county of Suffolk, of the Commonwealth of Massachusetts, have invented a new and useful Improvement in Refrigerators or Butter-Coolers; and I do hereby declare the same to be described in the following specification and represented in the accompanying drawings, of which—

10 Figure 1 is a front elevation, Fig. 2 a transverse section, and Fig. 3 a longitudinal section, of a refrigerator or butter-cooler of my improved kind, this latter section showing the rear parts of its rotary cells.

15 The nature of my invention is duly set forth in the claim hereinafter presented.

In such drawings, A denotes a box, chest, or ice-holder, having in its front one or more openings, a, each of which is for reception of 20 a revoluble cell, B, composed of a rectangular frame, b, a disk, c, a semi-disk, d, and a glass pane, e, arranged substantially as represented. The frame b fits the opening a, and is pivoted therein, so as to be revoluble horizontally, the pivots shown at f, f' being at the 25 middles of the two horizontal edges of the said frame. From the lowermost of the two pivots of each frame a crank, g, extends, as shown, and is connected at its wrist to one end of a 30 spiral spring, h, whose other end is either fixed to the wrist of another of the cranks or to the case A. From the case there is extended a stop, i, for the frame to bring up against when the revoluble cell is open or

35 closed—that is, in either of its two extreme positions. In some cases the cell may be constructed as shown at B'—viz., of a frame, b', a semicircular disk, c', and a glass pane, e', arranged as represented. In this latter con-

struction the pane is a flat sheet of glass; but 40 in the cell B such pane is a curved sheet of glass semicircular in transverse section. The cell is revolvable in either direction one hundred and eighty degrees, the frame being provided with notches n, n' to receive the stop, 45 in order to admit of the frame being so revolved, and stopped when either side of it is flush with the outer face of the ice-holder.

On a mass or a series of lumps of butter being placed in a cell, B, the latter can be revolved so as to carry the mass or lumps within the ice-holder or out thereof, as occasion may require, the said ice-holder being to contain ice for keeping cool the air within it.

It will be seen that when a cell is either 55 open or closed, as mentioned, it closes the opening a in which it is placed, so that little, if any, cool air can escape from the ice-holder or warm air enter it; also, that we have by the spring and crank and stop i of each cell a 60 ready means of holding the cell in either a closed or open position—that is, either turned outward or inward relatively to the ice-holder, such spring and crank readily admitting of the cell being so revolved. 65

I claim—

The combination of the ice-holder provided with one or more cell-receiving openings and a stop to each, as described, with a revoluble cell, essentially as explained, arranged in and 70 pivoted to the opening, and provided with a crank and spring, all being adapted and to operate substantially as represented.

ORRIN MILO WHITMAN.
